PHOTOFASH LAMP

Oliver William Hopkinson, Jr., Newark, and Paul Barringer Tully, Bloomfield, N. J., assignors to Westinghouse Electric & Manufacturing Company, East Pittsburgh, Pa., a corporation of Pennsylvania

Application December 30, 1941, Serial No. 424,844

2 Claims. (Cl. 67—31)

This invention relates to photo-flash lamps and more particularly to photo-flash lamps having an enclosing radiation permeable envelope comprised of an organic plastic such as cellulose acetate, and of the general character of lamp described in copending application, Serial No. 298,276, filed October 6, 1939, by M. J. Neumann de Margitta, assigned to the same assignee as this application and issued March 24, 1942 as Patent Number 2,227,481.

In the commercial production of a photo-flash lamp of the type described and claimed in said patent, it is preferable that the lamp structure, per se, be adapted to be assembled and completed with the minimum of manual effort and a maximum of high speed mechanical effort characteristic of modern lamp manufacturing practice.

One of the objects of the present invention is to provide a lamp structure which is adapted to be assembled and manufactured in accordance with modern high speed lamp manufacturing practices and upon modern high speed lamp manufacturing machinery.

Another object of the present invention is to provide a two-piece envelope comprised of molded cellulose acetate material with previously sealed-in leads, the two-piece envelope adapted to be mechanically joined together, hermetically sealed at the joint into a lamp assembly and exhausted, filled with an oxygen atmosphere, sealed from the atmosphere and based in a sequence of automatic mechanical operations characteristic of modern high speed lamp manufacturing equipment.

Still another object is to provide an improved means for sealing-in lead wires through one of the parts of said two piece envelope.

A further object is to provide an improved means for attaching and securing a base to the finished lamp.

Other objects and advantages will be apparent as the invention is more fully hereinafter disclosed.

In accordance with these objects, we have evolved and constructed the improved photo-flash lamp illustrated in the accompanying drawing wherein—

Fig. 1 is a side elevational view of the improved photo-flash lamp of the present invention;

Fig. 2 is an enlarged broken-away sectional view along plane 2—2 of Fig. 1, showing improved features of the present invention;

Fig. 3 is a cross-sectional view along plane 3—3 of Fig. 2;

Fig. 4 is an enlarged section along plane 4—4 of Fig. 2 before sealing the nipples on the wires;

Fig. 5 is another sectional view similar to Fig. 4 and showing the lead wire sealed in its nipple in accordance with the present invention;

Fig. 6 is a perspective view of an improved lead-in wire forming one feature of the present invention;

Fig. 7 is a sectional view along plane 7—7 of Fig. 5 illustrating assembly of the lead-in wire with its nipple or associated portion of the envelope;

Fig. 8 is an enlarged sectional view illustrating the retention of the base on the envelope and constituting a feature of the present invention.

Referring to the drawing, the photo-flash lamp 15 of the present invention comprises essentially a two-piece envelope E¹—E², each member comprised of radiation permeable molded cellulose acetate or material of like character, joined together in a sealed mechanical interlock joint J, 20 as more particularly set forth in co-pending application of R. L. Kreidler, Serial No. 393,320, filed May 14, 1941, and assigned to the same assignee and issued November 9, 1943 as Patent Number 2,333,725. The said envelope encloses 25 from the atmosphere aluminum foil or shreds A and ignition means F and contains an atmosphere of oxygen under pressure, as heretofore provided in the art. According to the present invention a base B is applied in novel manner to the bottom member E² of the envelope.

In the assembly indicated in the drawing, the two-piece molded envelope E¹ and E² consists of a dome-shaped upper chamber or bulb piece E¹ and a dish-shaped bottom member or press piece E², the open ends thereof being adapted to be telescoped together in a mechanical interlocking arrangement such as indicated by annular bead 10 engaging annular groove 11 on and in the outer and inner surfaces respectively of parts E¹ and E². A sealing compound (not shown) is preferably included within this interlocking joint, and if so desired another sealing composition 12 may be applied at the outside of the joint for 40 additional security of seal.

Prior to seal-joining members E¹ and E² together, part E¹ is filled with the desired amount of aluminum foil or shreds A and ignition means F is secured in position in part E². After seal 50 joining parts E¹ and E² together, the interior of the interior of the envelope E¹ and E² is evacuated, filled with an atmosphere of oxygen under pressure and then is sealed from the atmosphere. It is desirable to have operations performed mechanically and automatically as herefore prac-

ticed in high speed lamp manufacture on modern lamp making equipment.

The arrangement provided on part E^2 facilitates the obtainment of this desired result. As indicated in the drawing (Fig. 2) part E^2 is provided with a base-receiving portion or neck such as cylindrical extension R which depends from and is reenforced by a portion of said part E^2 integral with and flaring radially from the upper end of said neck, said neck also being provided with a bottom wall P forming part of the envelope. Lead-in support wires W_1-W_2 for ignition means F pass through this bottom wall as hereinafter described. Likewise an exhaust means or integral tubulation T depends from said bottom wall. The tubulation T is ultimately sealed after exhaust of the envelope and refilling of the same with combustion-supporting gas such as oxygen. The provision of this exhaust tube facilitates the manufacture of the device according to modern lamp manufacturing practices and equipment adapted for production of tipless type of lamp.

The problem of passing lead-in wires W_1-W_2 through the plastic material of envelope E^1-E^2 in a joint sealed to the atmosphere and supporting ignition means F within the envelope E^1 and E^2 , is primarily mechanical in nature as the plastic material comprising the envelope E^1 and E^2 cannot be fusion-welded onto the surface of lead-wires W_1 and W_2 . This difficulty is overcome in the arrangement shown by providing lead-in support wires W_1-W_2 with flattened areas or sections $13-13'$ below bottom wall P and extending said wires through and sealing the flattened sections in tubular nipples L_1 and L_2 also depending from and integral with said bottom wall. The nipples are intimately applied to the flattened areas. This operation in part may be readily accomplished mechanically. Following pressure molding of nipples L_1 and L_2 about the flattened areas $13-13'$ of lead-in wires W_1-W_2 , the extending ends C_1-C_2 of the wires may be heated in an open flame to a temperature which will effect fusion welding of said nipples to the wire surface, thus forming a hermetically sealed joint therebetween.

The advantages gained by providing lead wires W_1-W_2 with flattened areas is indicated in Figs. 4 to 7 inclusive, wherein Fig. 4 shows the wire (W_1), illustrated in perspective in Fig. 6, inserted in position in nipple L_1 with flattened area 13 disposed adjacent the bottom end of the nipple. Fig. 5 shows the relative position of the parts after pressure molding nipple L_1 to the flattened area 13 ; and Fig. 7 shows the nature of the pressure molded joint with the edge openings therealong requiring the fusion sealing for effecting complete hermetical closure thereof.

The arrangement shown provides a ready means for sustaining filament F in desired position within the envelope E^1-E^2 and a ready means for hermetically sealing the lead-in support wires W_1 and W_2 on which said filament is mounted. In general, it is exceedingly difficult to obtain a tight seal between the plastic material comprising the envelope E^1-E^2 and the metal comprising the lead-in support wires W_1 and W_2 , as the seal therebetween must be essentially a pressure union. The cellulose acetate is heated by any convenient means to a temperature at which it is plastic and is then compacted and pressure molded around the flattened wire surface. Hermetic pressure sealing is difficult to obtain with a rounded wire surface, and

the provision of flattened areas $13-13'$ on wires W_1-W_2 has been found to overcome this difficulty and to provide opposed and relatively wide flattened surface areas against which the molding pressure may be applied. However, in such an arrangement, the plastic material tends to flow around the thinned edges of the flattened wires, substantially as indicated in Fig. 7 to leave somewhat V-shaped passageways which may extend the entire length of the flattened section. We have found that these openings may be effectively sealed following pressure molding by heating the extending flexible conductors C_1-C_2 to a temperature which, by conduction therewith to flattened sections $13-13'$, results in the substantial fusion of the plastic material next adjacent the surface of the flattened areas. This fusion of plastic to metal occurs very definitely at portions of the wires next adjacent to the junction of the flattened areas and flexible conductors C_1 and C_2 , with consequent sealing of the plastic to metal joint therebetween and the closing of the V-shaped passageway at the sides thereof.

It will be noted that the nipple L_1-L_2 as well as tubulation T depend from the bottom of the envelope but are situated in the completed lamp within the base B . Said base comprises a cylindrical metal shell the lower end of which is closed by a plug 16 of electrically insulating material, said plug having an electrically conducting metal center insert or contact terminal 18 in the outer face thereof. The plug and insert are each provided with an opening therethrough for passage of one of the flexible conductors C_2 into a position where it may be secured by solder or otherwise in said insert 18 . Furthermore when the base B is put in position on the cylindrical neck portion R , the other conductor C_1 is located in the space gap between the side wall of cylindrical portion P and the inner side wall of base B and hooked through a slot 17 so its end may be soldered, as at 18 , to the outside surface of said base as indicated in Fig. 2.

The base B , thus positioned on cylindrical portion P , is mechanically secured in position by peening the base side walls inwardly at a plurality of points 20 substantially as indicated in the drawing. The center punch or peened indentations 20 are made at parts of the bottom member E^2 which provides relatively thick walls and next the end of neck R which is reenforced by the flaring portion of said member, and thus obtains a definite embedding of the pricked part of metal in the plastic rather than a springing of the plastic. The mechanical attachment of the base B to neck P as thus obtained may be augmented by a cement joint between the inner surface of the base B and the neck, if desired.

Another advantageous feature of the present invention is the provision of exhaust tube T in press P of section E^2 of the envelope E^1-E^2 . The provision of this exhaust tube facilitates the manufacture of the device according to modern lamp manufacturing practices and equipment adapted for the production of the tipless type of incandescent filament lamp.

It is believed apparent from the above description of the improved photo-flash lamp of the present invention that the same may be widely modified without essential departure therefrom and that the invention is applicable in whole or in part to other lamps than photo-flash lamps, and all such modifications and adaptations are

contemplated as may fall within the scope of the following claims:

We claim:

1. In a lamp provided with a radiation-permeable envelope comprised of a material of the character of organic plastic having a substantially radially flaring portion and a hollow cylindrically shaped neck the upper end whereof is integral therewith whereby said flaring portion reenforces the neck at the end thereof next the flaring portion, and a base member therefor, said base member comprising a cylindrical metal shell having an inside diameter approximating and at least as large as the outside diameter of the said neck and having a depth substantially greater than the length of said neck, and means to secure said base in position over the said neck, said means comprising a plurality of inwardly extending pointed areas in the side wall and next the upper end of the said base member mechanically and permanently engaging in corresponding pointed depressed areas in the surface

of said neck next the upper end thereof reenforced by said flaring portion.

2. In a lamp provided with a radiation-permeable envelope comprised of a material of the character of organic plastic having a substantially radially flaring portion and a cylindrically shaped neck the upper end whereof is integral therewith whereby said flaring portion reenforces the neck at the upper end thereof next the flaring portion, said neck being hollow and having portions on its side wall thick in a cross-sectional plane and portions thereof thin on the same cross-sectional plane, and a base member therefor, said base member comprising a cylindrical metal shield fitting at its sides around said neck, and having a plurality of inwardly extending peen points mechanically and permanently engaging in the said plastic neck at parts thereof where the wall of said neck is thick and reenforced.
